MULTIPLE TIME SWITCH

Joseph Camille Rivet, Montreal, Quebec, Canada

Application February 7, 1952, Serial No. 270,408

6 Claims. (Cl. 200—33)

1

The present invention relates to a time switch mechanism and more particularly to a multiple coin and time controlled switch mechanism.

The general object of the invention is the provision of a multiple time switch mechanism for closing a plurality of electric circuits in succession and for a predetermined time period.

An important object of the present invention is the provision of a switch operating mechanism whereby a plurality of electric light circuits may be operated for a selected time period by coin control means.

Another object of the present invention is the provision of a coin and time controlled multiple switch mechanism for closing a plurality of electric circuits for a predetermined time period, including means for preventing the accidental re-opening of said electric circuits after cessation of the operation of the circuit closing means.

A further object of the present invention is the provision of the device of the character described which will be very efficient and reliable in operation.

Still another object of the present invention is the provision of a multiple time switch mechanism which may control a large number of electric circuits although being relatively small and compact.

The foregoing and other important objects of the present invention will become more apparent during the following disclosure and by referring to the drawings in which:

Figure 1 is a perspective view of a votive assembly of lamps using the time switch mechanism according to the invention;

Figure 2 is a plan section taken across the box housing the time switch mechanism;

Figure 3 is a cross-sectional elevation taken through the mechanism along line 3—3 of Figure 6 and showing a switch in open position;

Figure 4 is a view similar to that of Figure 3 showing the switch being closed;

Figure 5 is a perspective view of one switch in closed position;

Figure 6 is a section along line 6—6 of Figure 3;

Figures 7, 8 and 9 are electric diagrams showing various stages of operation of the arrangement according to the invention; and

Figure 10 is an enlarged view of one of the plurality of switches according to the invention.

Referring now more particularly to the drawings in which like reference characters indicate like elements throughout, the letter A indicates a panel carrying a plurality of lamps B connected by an electric cable C to a box D containing the mechanism according to the invention, which is

itself connected to electric elements housed in a coin receiving container E by means of electric wires F. The time mechanism is connected to an electric outlet G by means of cable H. The box D forms an oil bath 1 at its bottom in which is immersed a shaft 2 rotated at a constant speed by means of gear 3 keyed to the middle portion of said shaft, and meshing with a worm 4 driven by a suitable electric motor and speed reducing unit 5 as shown in Figure 2. On the shaft 2 are keyed on both sides of the gear 3 a plurality of spaced clutch plates 6 having an inner flange 7 in contact with said shaft 2 and each engaging the central opening of a frictionally rotated disc 8 in frictional contact with the corresponding clutch 6. A compression spring 9 is disposed at each end of the shaft 2 to press the alternating clutch plates 6 and discs 8 on each side of the gear wheel 3 one against the other. Flanges 10 formed on the shaft 2 abut the inner clutch plates 6 adjacent the gear wheel 3 while outer slideable flanges 11 are disposed intermediate the coil springs 9 and the outer discs 8. The pressure exerted by the coil springs 9 will be adjusted by means of nuts 9' so that the discs 8 will normally rotate with the shaft 2 but will be prevented from rotating by a slight stopping force exerted at the periphery thereof. For that purpose the discs 8 are provided with a square-shaped notch 12, as shown in Figures 3 to 5, for receiving the square inner end 13 of the long leg 14 of a T-shaped member 15. The long leg 14 of the T-shaped member 15 is longitudinally slideable and pivotable in a flared bore 16 of a rack 17 extending above the shaft 2 and the plurality of clutch plates 6 and discs 8.

The cross leg 18 of the T-shaped member 15 is prevented from rotating in a horizontal plane by engaging a transverse groove 18' made at the upper face of rack 17. Said cross-leg 18 is coated at one end with a silver layer 19 forming an electric contact adapted to abut the silver coated head 20 of a pin 21 slidably mounted on a bracket 22, urged downwardly by spring 21' and forming a stationary electric contact secured to a frame member 23 made of electric insulating material. The opposite end of the cross-leg 18 of the T-shaped member 15 has a bevelled recess 24 at one of its side faces to receive a wedge 25 mounted on an endless chain 26 adapted to travel within a guiding channel 26' extending at the upper face of the rack 17 in a direction perpendicular to the several grooves 18' and consequently to the cross-legs 18 of the T-shaped elements 15.

It will be seen that the bevelled ends 13 of said

elements 15 will normally engage the notch 12 of the corresponding disc 8 to prevent rotation of the latter, as shown in Figure 3, in which case the T-shaped member 15 is in its lower position, the electric switch being open. When the wedge 25 of the travelling endless chain 26 comes in contact with the recess 24 of the side leg 18 of the T-shaped member 15, the latter is caused to pivot so as to take an inclined position as shown in Figure 4 with the contact 19 abutting the head 20 while at the same time the square end 13 of the long leg 14 disengages the notch 12, and is automatically displaced to take a position opposite the periphery of the disc 8.

Upon further travelling of the chain 26, the wedge 25 clears the cross-leg 18 of the T-shaped member 15 whereupon the long leg 14 of the latter takes a slightly inclined position with the end 13 resting on the periphery of the disc 8. In this latter position the side leg 18 of the member 15 will slightly compress the spring 21' of the pin 21 of the stationary electric terminal.

After a complete revolution of the disc 8 the square end 13 of the T-shaped member 15 again engages the notch 12 of said disc 8 whereby the long leg 14 assumes its lower vertical position and electric contact is stopped between the member 15 and the pin 21 as shown in Figure 3. It will be understood that there is a clutch plate 6, a disc 8, a T-shaped member 15 and a stationary electric contact 21 for each of the lamps B thereby forming as many time switches for closing their respective electric circuit for a predetermined time controlled by the speed of rotation of the shaft 2 and the diameter of the discs 8.

Despite the fact that each disc 8 rotates at a slow speed as compared to the rate of travel of the chain 26 and consequently to the short time periods during which a wedge 25 engages the cross-leg 18 of the T-shaped member 15, it will be noted that on account of the pivotal movement of the T-shaped member 15, the end 13 of the latter cannot drop again into the notch 12 of the disc 8 after passage of the wedge 25.

As shown in Figure 2, there is preferably an endless chain 26 for each set of T-shaped elements 15 on each side of the central worm gear 3. These endless chains are trained over sprocket wheels 27 conveniently mounted on brackets 28 and driven by a common motor 29 through the worm 30 and worm gear 31 disposed at one end of the box D. On the shaft 32 of the motor 29 is keyed a wheel 34 provided with a tooth 35, shown more particularly in Figure 7, adapted to lift the actuating arm 36 of a switch 37 for stopping operation of the motor 29 after one rotation of its shaft 32.

The speed ratios of the shaft 32 and chains 26 is such that the wedges 25 on said chains will travel only the distance necessary to engage one T-shaped member 15 and clear the same. Said wedge will stop before engaging the next T-shaped member 15. The wheel 34 is also provided with a pin 38 to operate a counting device 39 for registering the number of actuations of the motor 29, that is the number of coins deposited in the coin controlled mechanism.

As shown in Figures 7 to 9 the coin receiving box E comprises a coin chute 40 communicating with the coin container 41, a coin stopping arm 42 and a switch actuating arm 43 extending within said chute 40. The coin stopping arm 42 is connected to suitable levers 44 and to a press button 45 whereby depression of said button 45 will cause retraction of arm 42 as shown in Fig-

ure 8. Operation of the arm 43 by a coin, as shown at 46 in Figure 8, will close the switch 47. The box E also comprises a pilot lamp 48 and a holding relay 33, the actuated bar 62 of which is provided with a stopping arm 63 adapted to project within the chute 40, as shown in Figure 8, for preventing additional coins 46' from reaching the switch arm 43 during operation of the device. Upon closing of the main switch 49 the electric motor 5 will be energized to rotate the shaft 2 at a uniform constant speed through the circuit: switch 49, wires 50, 51, motor 5, wires 52, 53 and switch 49. Upon closing of the switch 47 by a coin 46, the following circuit is closed: switch 49, wire 50, pilot lamp 48, wires 54, 55, switch 47, wire 53, and switch 49. At the same time the following parallel circuit is closed: main switch 49, wire 50, wire 56, electric motor 29 driving the endless chains 26, wires 57, 55, switch 47 and wire 53 back to the main switch 49. Furthermore, the following circuit is closed at the same time: switch 49, wires 50, 58, electromagnet 59, wires 60, 54, 55, switch 47, wire 53, back to the main switch 49. Upon energization of the electromagnet 59, the pivoted bar 62 is attracted and connects the wire 60 to wire 61 itself connected to switch 37. As soon as wheel 34, driven by the electric motor 29, has started to rotate, the actuating arm 36 of the switch 37 leaves the tooth 35 of said wheel 34 thereby closing said switch 37 and connecting the wire 61 to the wire 53. As soon as the coin 46 has passed the arm 43 of the switch 47, said arm 43 extending within the coin chute 40, said switch 47 breaks the circuit: wire 55, switch 47 and wire 53 as shown in Figure 9. But the motor 29 continues to operate through the following holding circuit: switch 49, wires 50, 56, motor 29, wires 57, 54, 60, bar 62, wire 61, switch 37, wire 53 and main switch 49. This holding circuit will remain energized until the switch 37 returns to its open position. The arm 63 projecting within the coin chute 40 will retain any additional coin 46' until the switch 37 opens, that is until the lighting operation of one of the lamps B is completed.

The lamps B are lighted by the following circuits: (a) wires 58, 65, primary of transformer 66, wires 67 and 53; (b) ground 68, secondary of the transformer 66, wire 69, lamp B, wire 70, bracket 20, the contact pin 21 and T-shaped member 15 which is grounded at 71.

The friction discs 8 are provided with radial grooves 72 to collect any foreign matter which may accumulate between their side surface in contact with the associated clutch plate 6.

It will be noted that the wedges 25 on the endless chains 26 are so spaced that as one wedge 25 is leaving one row of T-shaped members 15, the wedge 25 on the other chain 26 will start to engage the other row of said members.

The multiple control time switch, according to the invention, is operated as follows:

A coin 46 is inserted within the chute 40 and rests against the stop arm 42 as shown in Figure 7. The push button 45 is then depressed to allow the coin 46 to drop onto the arm 43 of the switch 47 which closes the circuit to the pilot light 48, the electromagnet 59 and to the electric motor 29. As soon as the latter starts to operate the electric switch 37 is closed thereby closing the holding circuit for the motor 29 and the electromagnet 59, the pivoted bar 62 of which is attracted to close the chute by means of the projecting arm 63 in order to prevent any additional coin to operate switch 47.

The motor 29 continues to operate and causes a wedge 25 on either one of the chains 26 to lift and pivot a T-shaped member 15 thereby closing the electric circuit to one of the lamps B. The latter circuit is again opened after one complete revolution of the disc 8, when the lower end 13 of said T-shaped member 15 again engages the notch 12 of the disc 8.

Referring to Figures 3 to 5, it will be noted that the end 13 of T-shaped member 15 and the notch 12 of disc 8 are square and fit each other within substantially close tolerances. Otherwise, due to the slow speed of rotation of disc 8 relatively to the time of actuation of the member 15 by the wedge 25, the end 13 would have time to start to engage notch 12 and then disengage and reengage the same upon dropping a coin into the machine. This could happen when all the lamps B are lighted and a coin is dropped into the machine only a short time after one of said lamps becomes deenergized.

It has been stated in the above description that the wedge 25 moves intermittently between successive T-shaped member clearing positions. It is obvious that said wedge 25 may be so arranged as to come to rest in successive positions engaging said T-shaped members 15, whereby the lamp B which was last lighted will remain so until the main switch 49 is opened.

While a preferred embodiment according to the invention has been illustrated and described it is understood that various modifications may be resorted to without departing from the spirit and scope of the appended claims.

I claim:

1. A time switch mechanism comprising a frictionally rotated disc having a notch at its periphery, an elongated member adapted to take a first position engaging said notch to stop rotation of said disc and a second position resting on the periphery of said disc, a side extension on said member, means engageable with said extension to raise and pivot said member from said first to said second position, electric contacts associated with and operated by said member and a rack member for said elongated member having a bore with flaring walls for receiving said elongated member, said rack member being disposed between said disk and said side extension.

2. A time switch as claimed in claim 1, said elongated member having a second side extension forming one of said electric contacts and a stationary member forming the other of said contacts, abutting said second extension when said elongated member is in said second position. 55

3. A time switch as claimed in claim 1, said elongated member having a second side extension forming one of said electric contacts, a stationary member forming the other of said contacts, abutting said second extension when said elongated member is in said second position, said bored rack member having a transverse groove at its upper face for receiving said extensions.

4. A time switch mechanism comprising a frictionally rotated disc having a notch on the periphery thereof, an up-right T-shaped member having its main leg longitudinally and pivotally displaceable from a first notch engaging position to a second disc periphery abutting position, means engageable with a side leg of said member to move the latter from said first to said second position, an electric contact abutting the other of said side legs when said member is in said second position, and a bored rack through which extends the long leg of said T-shaped member, said rack having a groove at its upper face for receiving said side legs.

5. A multiple time switch mechanism comprising a driving shaft, a plurality of frictionally rotated discs mounted on said shaft, said discs having a notch on the periphery thereof, a plurality of upright T-shaped members extending side by side and having their main leg longitudinally and pivotally displaceable from a first notch engaging position to a second disc periphery abutting position, a flexible member displaceable underneath one side leg of said T-shaped members, and across a row of the same, a boss on said endless flexible member, engageable with said side legs to transfer successively said T-shaped members from said first to said second position and electric contacts closeable upon said transfers.

6. A multiple time switch mechanism as claimed in claim 5 including a bored rack through which extend the long legs of said T-shaped members, said rack having at its upper face a plurality of transverse grooves for receiving the side legs of said T-shaped members and a longitudinal channel for receiving said flexible member.

JOSEPH CAMILLE RIVET.
